US00D763254S

(12) **United States Design Patent**
Aumiller et al.

(10) **Patent No.:** US D763,254 S
(45) **Date of Patent:** ** Aug. 9, 2016

(54) **ELECTRONIC DEVICE**

- (71) Applicant: **Samsung Electronics Co., Ltd.**, Suwon-si (KR)
- (72) Inventors: **Curtis Aumiller**, San Jose, CA (US); **Pranav Mistry**, Cupertino, CA (US); **Chengyuan Wei**, Dalian (CN)
- (73) Assignee: **SAMSUNG ELECTRONICS CO., LTD.**, Suwon-Si (KR)
- (**) Term: **14 Years**
- (21) Appl. No.: **29/508,624**
- (22) Filed: **Nov. 7, 2014**

Related U.S. Application Data

- (63) Continuation of application No. 29/453,820, filed on May 3, 2013, which is a continuation of application No. 29/449,661, filed on Mar. 15, 2013, now Pat. No. Des. 709,874.

(57) **CLAIM**

The ornamental design for an electronic device, as shown and described.

DESCRIPTION

FIG. 1 is a top left front perspective view of an electronic device showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The dashed broken lines shown in the drawings represent portions of the electronic device that form no part of the claimed design.
